UNITED STATES PATENT OFFICE

94,876

DESIGN FOR A SHOE

Harry Clayman, Boston, Mass.

Application January 17, 1935, Serial No. 54,888

Term of patent 3½ years

To all whom it may concern:

Be it known that I, Harry Clayman, a citizen of the United States of America, and resident of the city of Boston, county of Suffolk, and State of Massachusetts, have invented a new, original, and ornamental Design for a Shoe, of which the following is a specification, reference being had to the accompanying drawing, forming a part thereof.

The figure is a perspective view of the shoe showing my new design.

I claim:

The ornamental design for a shoe, as shown.
HARRY CLAYMAN.
